CLAIM

The ornamental design for a case for electronic device, as shown and described.

DESCRIPTION

FIG. 1 is a first front isometric view of a case for electronic device showing our new design;

FIG. 2 is a front view thereof; and,

FIG. 3 is a second front isometric view thereof.

The dot-dash broken line represents a boundary of the claimed design. The dash-dash broken lines depict unclaimed subject matter. The broken lines and unshaded surfaces bounded by broken lines form no part of the claimed design.
